E. ECHEVARRIA

TALKING MANIKIN

Filed Oct. 8, 1924

Patented June 16, 1925.

1,542,542

UNITED STATES PATENT OFFICE.

EDUARDO ECHEVARRIA, OF GRANITE CITY, ILLINOIS.

TALKING MANIKIN.

Application filed October 8, 1924. Serial No. 742,312.

To all whom it may concern:

Be it known that I, EDUARDO ECHEVARRIA, citizen of Mexico, residing at Granite City, in the county of Madison and State of Illinois, have invented certain new and useful Improvements in Talking Manikins, of which the following is a specification.

This invention relates generally to novelty devices such as are used in store windows or the like, the present invention having particular reference to a manikin arranged in connection with a talking machine to have the sound conducted through a tube that leads to the mouth of the manikin, the invention having for an object the provision of a novel device of this sort that is provided with means whereby the mouth of the manikin may move as if in talking or singing, and one or more of the limbs make appropriate gestures.

For further comprehension of the invention, and of the objects and advantages thereof, reference will be had to the following description and accompanying drawing, and to the appended claims in which the various novel features of the invention are more particularly set forth.

Fig. 1 of the drawing is a perspective view of a device having the invention embodied therein.

Fig. 2 is a central longitudinal vertical sectional view thereof.

Fig. 3 is a detail horizontal sectional view taken on the line 3—3 of Fig. 2.

Referring now to the drawing, the reference numeral 10 indicates a box or cabinet on top of which a manikin 11 is fixed. In the box 10 is an electric motor 12 having a worm pinion 13 on its shaft 14 that meshes with a worm gear 15 on a vertical shaft 16 that has a turntable 17 fixed on its upper end, this turntable being adapted to have suitable disk records placed thereon. The records are engaged by the needle of an ordinary sound box 20 that is mounted on a tone arm 21 that has a pivotal connection with a tube 22 that leads upward through the hollow body of the manikin and is directed forwardly at its upper end as at 22' to terminate adjacent the mouth of the manikin. The lower jaw 23 of the manikin is hinged to the head as at 24 to swing in a vertical plane, while a rubber strip 25 may cover the space between the neck and the bottom of the jaw.

In order to cause the jaw 23 to move in a

manner simulating the movement of a person speaking or singing I provide the following means. Extending upward through the manikin is a second tube 28 of larger diameter than the tube and enclosing the latter. This tube is formed with an enlarged lower end 28' in which is mounted a horizontally disposed helical fan 29 that may be supported by a suitable bracket 30. This fan is fixed on the upper end of a vertical shaft 31 that has a bevel gear 32 fixed to its lower end, this gear meshing with a like gear 33 on the lower end of the motor shaft 14. Extending across the tube 28, just above the fan 29 is a partition element 35 formed with a series of slotted apertures 36. Slidably mounted on this partition is a valve plate 37 having like slotted apertures 38 that are adapted to be moved into and out of registry with the apertures 36 in the partition. Fixed to one edge of this plate 37 is a rod or stem 39 that projects from the tube and has a slot and pin connection as at 40 with the upper end of a bell crank lever 41 that is fulcrumed as at 42 in the box 10 and has a roller 43 on its other end that engages a cam 44 fixed on a stub shaft 45 to which is also fixed a worm gear 46 that meshes with a worm pinion 47 on the turntable shaft 16.

A coiled tension spring 48 is connected at one end to the lever 41 and at its opposite ends to a suitable fixed part and serves to keep the roller 43 engaged with the cam 44. Fixed to the jaw 23, adjacent its pivotal point, and projecting rearwardly across the neck of the manikin is a rigid flap 50 that has an opening therein to accommodate the tube 22. This flap may if desired be weighted as at 51 to act as a counterbalance to hold the jaw member raised. An operative connection may be effected between the flap 50 and one of the arms, indicated at 54, of the manikin by means of a link 55 that is attached at its upper end to the flap and extends downward to connect at its lower end to an arm 56 fixed on a stub shaft 57 on which the arm 54 of the manikin is fixed, this shaft being suitably mounted in the body of the manikin. The cabinet 10 may be provided with doors 60 for access to the mechanism therein.

As will be apparent from the above description the cam 44 will control the movement of the valve plate 37, and when the latter is moved to open position the blast of air driven by the fan 29 through the

tube 28 will cause the flap 50 to swing upward and the jaw 23 to swing downward, while at the same time the arm 54 is moved.

Having thus described my invention what I claim as new and desire to protect by Letters Patent of the United States is as follows:

1. In combination, a manikin, a sound reproducing device including a motor, a sound conducting tube leading from the said device to the mouth of the manikin, a fan driven by said motor, an air conduit leading from said fan to the neck of the manikin, a hinged lower jaw on said manikin, a flap fixed to said jaw and normally extending across the said conduit, and a valve operable by said motor for controlling the flow of air through said conduit.
2. In combination, a manikin, a sound reproducing device including a motor, a sound conducting tube leading from the said device to the mouth of the manikin, a fan driven by said motor, an air conduit leading from said fan to the neck of the manikin, a hinged lower jaw on said manikin, a flap fixed to said jaw and normally extending across the said conduit, and a valve operable by said motor for controlling the flow of air through said conduit, said valve comprising a perforated partition in said conduit and a slideable perforated plate above said partition, a cam driven by said motor, and a rock lever engaged at one end with said cam to be moved by the latter and connected at its other end to the said plate to move the same.
3. In combination, a manikin, a sound

reproducing device including a motor, a sound conducting tube leading from the said device to the mouth of the manikin, a fan driven by said motor, an air conduit leading from said fan to the neck of the manikin, a hinged lower jaw on said manikin, a flap fixed to said jaw and normally extending across the said conduit, and a valve operable by said motor for controlling the flow of air through said conduit, said valve comprising a perforated partition in said conduit and a slideable perforated plate above said partition, a cam driven by said motor, and a rock lever engaged at one end with said cam to be moved by the latter and connected at its other end to the said plate to move the same.

4. In combination, a manikin, a sound reproducing device including a motor, a sound conducting tube leading from the said device to the mouth of the manikin, a fan driven by said motor, an air conduit leading from said fan to the neck of the manikin, a hinged lower jaw on said manikin, a flap fixed to said jaw and normally extending across the said conduit, and a valve operable by said motor for controlling the flow of air through said conduit, a pivoted arm on said manikin and an operative connection between said flap and said arm.

In testimony whereof I have affixed my signature:

EDUARDO ECHEVARRIA.
